UNITED STATES PATENT OFFICE.

GEORGE GERRARD, OF GLASGOW, SCOTLAND, ASSIGNOR TO JOHN C. WILSON & CO., OF SAME PLACE.

APPARATUS FOR BURNING HYDROCARBON OR OTHER OILS.

SPECIFICATION forming part of Letters Patent No. 510,170, dated December 5, 1893.

Application filed December 22, 1890. Serial No. 375,542. (No model) Patented in England December 7, 1889, No. 19,730.

To all whom it may concern:

Be it known that I, GEORGE GERRARD, a subject of the Queen of Great Britain, residing at Glasgow, in the county of Lanark, Scotland, have invented new and useful Improvements in Apparatus for Burning Hydrocarbon or other Oils, (for which I have obtained Letters Patent in Great Britain, No. 19,730, dated December 7, 1889,) of which the following is a full, clear, and exact description, reference being had to the accompanying drawings, forming a part of this specification.

My invention relates to apparatus for burning hydro-carbon and other oils, and has for its object the improvement of the construction, durability and efficiency of such apparatus.

To these ends, it consists in combining a vertically arranged vaporizing coil with an oil reservoir by means of a goose neck or siphon shaped pipe, so that the oil shall enter the coil in an opposite direction from that from which it proceeds from the reservoir and be vaporized as it gradually descends in the coil; also in the combination with a vaporizing coil whether arranged parallel to or at right angles with the oil reservoir, of a burner jet arranged to discharge centrally through the convolutions of said coil and affixed to the extended end of the lowest convolution, and a mixing and burning chamber of appropriate dimensions relatively to the diameter and length of the vaporizing coil and surrounding the same closely, said mixing and burning chamber being open at one end and closed at its other end and provided at the latter with an annular series of air apertures, and a rotating sleeve having a similar annular series of air apertures adapted to register therewith; also in the combination with the oil reservoir and the connecting tube, of a two-way port between the same communicating with the air and with the oil respectively, and valves to close either or both of said ports at will.

In the accompanying drawings illustrating my invention, in which like letters of reference indicate like parts in the several views, Figure 1 is an elevation of my improved apparatus. Fig. 2 is a detached view partly in elevation and partly in section, showing the goose neck connecting tube, the mixing and

burning chamber and the vaporizing coil and its burner jet. Fig. 3 is a top or plan view of the same on a larger scale. Fig. 4 is a vertical section of the oil reservoir and the two-way port between the same and the connecting tube; and, Fig. 5 is a similar vertical section of a modification thereof.

An oil tank or reservoir C of any convenient form, is provided for containing hydro-carbon or other oil, which is fed to the vaporizing device by means of a hand pump or in any other well known manner, or it may be supplied thereto by gravitation or otherwise. The vaporizing retort consists of a coil of pipe A A (see Fig. 2) the first convolution of which, secured to the perpendicular connecting pipe B bent round at its upper extremity, forms a goose neck or siphon shaped connection with the oil tank or reservoir C. This arrangement of the parts is an essential feature of my invention, in order that the oil passing through the connecting pipe B shall enter the vaporizing coil from the reservoir C and be vaporized as it gradually descends through the coil; thus the oil is delivered to the vaporizing coil at its first or top convolution, which is the hottest portion thereof, the effect being to cool the pipe at that point to preserve that portion from injury through over-heating, thus obviating the rapid deterioration to which the vaporizing coils as heretofore constructed are subject, owing to the hydro-carbon or other oil being fed primarily into the lower convolution or coolest portion of the said coil and passing as vapor to the upper convolutions or hottest portions thereof. The said vaporizing coil is preferably arranged vertically so as to be parallel or nearly so to the oil reservoir and the connecting tube. In addition to the advantage mentioned, by this arrangement of the tube and coil in parallel vertical planes the tube B operates in a measure, owing to its siphon form, to deliver the oil with a less expenditure of pressure to the vaporizing coil. Between the connecting tube B and the oil reservoir C is provided a two-way port shown in section, Fig. 4, which may be slightly modified as shown in section in Fig. 5. This port consists of a casing G having two passages H and I, the latter being provided with a long

pipe B' extending downward into the oil in the reservoir C. A screw plug L governs the port I and another screw plug J governs the port H. By closing the latter, connection between the vaporizing coil and the upper portion of the reservoir C is cut off, while the screw plug L governing the passage I opens or closes connection between the oil in the reservoir C and the connecting tube B secured to the top of the two-way port casing G. Thus the air and oil, or either, at pleasure, is admitted to the vaporizing coil through the connecting tube B from the reservoir C. In lieu of the two screw plugs shown in Fig. 4, a two-way cock M may be provided as seen in vertical section in Fig. 5. But the latter is useful only where either air or oil, but not both at the same time, is intended to be used.

By reference to Fig. 2, it will be observed that the lowest convolution of the vaporizing coil A has an extended end which is provided with an oil burning device having a burner nozzle D arranged perpendicularly so as to discharge the flame through the center, or nearly so, of the convolutions of the vaporizing coil. The coil and its burner tube are closely surrounded by and form part of a mixing and burning chamber E which is of appropriate dimension relatively to the diameter and length of the vaporizing coil, and is open at the top and closed at its base; said base portion is provided with an annular series of air apertures F, over which is placed a rotating sleeve F' having a similar set of air apertures adapted to register with the air apertures in the chamber E. Rotating this sleeve will open to a greater or less degree, as desired, the air apertures of the mixing and burning chamber E to the outer air; and the volume of the current of air within said chamber can thus readily be regulated. The flame proceeds practically from the top of the casing E which is thus its hottest portion. The said air apertures in the casing E must be in the lower portion thereof on a line with or beneath the burner tube D.

When starting the apparatus, a small quantity of hydro-carbon or other oil is poured into the casing E and lighted so as to cause the necessary preliminary heating of the vaporizing coil, or waste saturated with oil may be inserted therein and ignited for a similar purpose.

When air pressure is provided at the interior of the oil reservoir C, a portion of the air may be used to create a forced draft in the mixing chamber E when starting the apparatus, thereby greatly expediting or accelerating the preliminary heating of the vaporizing coil. A required before the apparatus can be put into automatic operation. For this purpose the port H of the two-way port G may be opened to establish connection between the upper portion of the reservoir C and the connecting tube B. Air is thus forced to and through the nozzle or burner D, and ascending through the casing E creates a draft which

causes a violent combustion of the oil or oily waste ignited in the chamber E for the preliminary heating of the vaporizing coil, and consequently tends to raise the latter very rapidly to a high temperature. The mixture of air and vapor in the casing E is effected through the air apertures F; or for the same purpose, in whole or in part, air may be forced through the passage H and thence through the connecting tube B and coil A so that the mixture of air and vapor may be had therein to a greater or less extent as may be desired.

I am aware that it is not new to use a coil as a vaporizer for the burning of hydro-carbon and other oils, and I do not claim such, but it is new with me to use a coil arranged parallel, or nearly so, to the reservoir, and connecting the two by a goose neck or siphon shaped pipe in order that the burner jet shall be below and on a line with the coil, also to arrange said vaporizing coil at right angles or nearly so to the reservoir, with a connecting tube between them, in order in both constructions, that the oil shall enter the coil at its hottest part and with greater ease and facility for the reasons mentioned.

The result of the construction and arrangement shown and described is that the oil is not vaporized until it enters and passes the first convolution of the coil, and the latter being detachably suspended within and enclosed within a casing closed at one end except by adjustable openings and open at the other end, both forming together a mixing and burning chamber (the mixture of the air and vapor being produced at the base of the said combined parts) a powerful induced upward current is produced in such mixing chamber, and the said mixture of air and vapor will not burst into flame until at or near the open end of said mixing and burning chamber, which is the point at which it is most desired for both heating and lighting purposes.

In all apparatus of this character heretofore made, in which the vaporizing coil was supplied with oil to form a gas by a flame enveloping said coil, the danger is the rising of the temperature of the coil too high and so disintegrating the gas and causing deposits of carbon on the inside of the coil which quickly choked it up. The leading feature of my invention is to regulate the temperature and prevent this deposit of carbon by constructing and arranging the coil and casing as described and so combining them as set forth to form between them the mixing and burning chamber to which outside cold air is admitted by adjustable apertures in the casing or outer walls of the mixing chamber and to the extended end of the vaporizing coil which constitutes the inner wall of the mixing chamber. Thus not only is air admitted to support combustion, but at the same time to control combustion that it may reach such extent only that the temperature will not rise above the point to prepare and efficiently vaporize

the oil without depositing carbon in the vaporizing coil or retort.

Having thus described my invention, what I claim as new, and desire to secure by Letters Patent, is—

- 5 1. The combination in a hydro-carbon burner, with an oil reservoir and a vertical connecting tube, siphon-shaped at its upper end, of a vaporizing coil retort arranged parallel, or nearly so, to said connecting tube, and provided on the extended end of its lowest convolution with a burner nozzle so disposed as to discharge its jet upward through the center of the vaporizing coil, and an inclosing tube or casing surrounding the burner and end of the coil, and forming thereby a mixing and burning chamber, with means to adjustably regulate the admission of air thereto; substantially as described.
- 10 2. The combination in a hydro-carbon burner, with an oil reservoir and a connecting tube leading therefrom, curved at its upper extremity, of a vaporizing coil retort detachably secured to said connecting tube at one of its ends, and provided at its other end with a burner nozzle arranged to discharge a flame through the center of the coil, an inclosing casing surrounding the burner and end of the coil, said parts forming together a mixing and
- 15 30 35 40 45 50 55 60 65 70 75 80 85 burning chamber; with adjustable apertures in the lower part of said casing operating to regulate the admission of air to said mixing and burning chamber and regulate the temperature therein; substantially as described.
3. The combination in a hydro-carbon burner with an oil reservoir and a connecting tube B leading therefrom, curved at its upper extremity, of a vaporizing coil retort A detachably secured to said connecting tube at one of its ends, and provided at its other end with a burner nozzle D arranged to discharge its flame through the center of the coil, and an inclosing casing or tube E surrounding the said burner and end of the coil retort, said parts forming together both a mixing and burning chamber, with means to adjustably regulate the admission of air to said chamber
- and control the temperature therein consisting of an annular series of holes F in the end of said casing near the burner, and a sleeve G surrounding said casing provided with holes registering with those in the casing; substantially as described.
4. The combination, in a hydro-carbon burner, of an oil reservoir and connecting tube leading therefrom to a vaporizing coil retort, and a casing surrounding said coil and forming therewith a mixing and burning chamber, of a two-way port between the reservoir and the connecting tube composed of the casing G having separate passages H and I and pipe B', adapted to communicate with the oil and the air respectively in said reservoir, and valve mechanism substantially as described operating to wholly or partly close either or both of said passages at pleasure; substantially as and for the purposes set forth.
5. In combination, forming a hydro-carbon burner, of a vaporizing coil retort detachably suspended within the casing, of a tube or casing closed at its lower end and open at its top, and having an adjustably closed bottom whereby the base of the casing may serve as a cup to receive oil for a preliminary heating, said parts being so arranged relatively that the flame of the initial heating passes through the mixing chamber; substantially as described.
6. In a hydro-carbon burner, the combination with a casing or tube closed at its lower end and open at its top, with a vaporizing coil having a burner on its lower convolution, said coil being detachably suspended within the casing and adjustable with relation to the reservoir connections, and said casing having adjustable air apertures at its base, and forming, in connection with the end of the coil retort, a mixing and burning chamber into which the admission of air and the control of the temperature therein may be regulated; substantially as described.

GEORGE GERRARD.
